UNITED STATES PATENT OFFICE

CHARLES PETRUNIN, OF TOLEDO, OHIO

AEROPLANE

Application filed November 28, 1927. Serial No. 236,097.

This invention relates to aeroplanes, but more particularly to relatively large aeroplanes capable of carrying a considerable number of passengers or amount of freight.

5 An object of this invention is to provide an aeroplane having a plurality of cabins so constructed and arranged that a relatively great load may be carried.

Another object of the invention is to so construct the wings of the aeroplanes that the resistance or impedance to the movement of the aeroplane is reduced to a minimum; a further object of the invention is to provide an aeroplane having the new and improved 15 features of construction and arrangement hereinafter described.

The invention is shown by way of illustration in the accompanying drawings, in which:

Fig. 1 is a top plan view of the aeroplane; 20 Fig. 2 is a side elevation of the aeroplane shown in Fig. 1; and Fig. 3 is a front elevation of the aeroplane.

The illustrated embodiment of the invention comprises an aeroplane having three sets 25 of wings, an upper set 1, an intermediate set 2, and a lower set 3. The upper set 1 of wings is considerably shorter than the wings 2, and in this instance, consists of three plates or segments spaced horizontally from each other. The wings may be constructed of any 30 material suitable for the purpose, and it is apparent that by so constructing the wings of less width and spacing them apart in the manner shown, the resistance to the travel of the 35 aeroplane is considerably reduced, and the aeroplane is enabled to effect sudden changes in direction of movement with the minimum amount of impedance.

The wings 2 extend considerably beyond 40 the ends of the wings 1, and in this instance, the set 2 of intermediate wings is composed of two plates of panels spaced horizontally from each other, and arranged beneath the outer wings of the set 1, the intermediate wing of 45 the set 1 being disposed in a plate between the wings of the set 2.

The lower wings 3, there being shown two 50 wings of this set, are disposed beneath the central wings 2 and are considerably shorter than the wings of the set 1. By this construction it

is manifest that a well balanced arrangement is secured.

Interposed between the sets of wings 2 and 3 are cabins 4 and 5 spaced transversely from each other and arranged adjacent the outer ends of the wings 3. The opposite ends of each of the cabins 4 and 5 are pointed so as to reduce the resistance to the travel of the plane, and these cabins are adapted to hold passenger or freight, and the motors for operating traction propellers are at opposite ends thereof. A feature of the invention resides in permitting ready access to the motors operating the propellers 6 so that in case one motor is disabled it may be readily repaired 60 by mechanics in the cabins 4 and 5, as will be understood.

Each of the cabins 4 and 5 is provided with a pair of supporting wheels 7 mounted on brackets connected to the underside of the 70 cabins intermediate the ends thereof. Positioned in rear of the supporting wheels 7 is a wheel 8 somewhat smaller than the wheel 7 and having its axis disposed closer to the cabin so that the aeroplane normally assumes an inclined position with the front or nose elevated from the tail in the usual manner. Positioned in front of the supporting wheels 7 and arranged therebetween is a wheel 9 of 75 similar size and similarly supported to the underside of the respective cabins. By providing a set of wheels or rollers for each cabin the liability of the aeroplane turning over when landing or starting is materially reduced, and the safety is accordingly enhanced. 80

Positioned between the cabins 4 and 5 and intermediate the sets of wings 1 and 2 is a cabin 10, the front end of which is pointed and extends beyond the outer ends of the cabins 4 and 5. A traction propeller 11 is positioned 90 in the front end of the cabin 10, and the motor is, therefore, accessible from the inside of the cabin. The cabin 10 extends rearwardly beyond the rear end of the cabins 4 and 5 and constitutes the tail 12 of the aeroplane, the 95 rudder 13 and elevating wings 14 being connected thereto in the usual manner. The cabin 10 may be of such size as to accommodate a considerable number of passengers or to carry a substantial amount of freight. 100

While I have shown and described the best embodiment of my invention known to me at the present time, it is to be understood that numerous changes in details of construction and arrangement of parts may be effected without departing from the spirit of my invention, especially as defined in the appended claims.

What I claim as new and desire to secure by Letters Patent is:

1. An aeroplane having three sets of wings arranged in vertically spaced relation, the middle wing being considerably longer than the remainder and the top wing being longer than the lower wing, and each wing being composed of horizontally spaced relatively narrow plates.
2. An aeroplane having three sets of wings arranged in vertically spaced relation, the middle wing being considerably longer than the remainder and the top wing being longer than the lower wing, and each wing being composed of horizontally spaced relatively narrow plates, two cabins disposed beneath the central wing and spaced from each other longitudinally of said central wing, and a cabin between said central wing and top wing positioned intermediate of said first cabin.
3. An aeroplane having two cabins disposed beneath the central wing and spaced from each other longitudinally of said central wing, a mounting consisting of two pairs of wheels arranged in transversely spaced relation, a smaller wheel in rear of and between each pair of main wheels, a similar wheel disposed in front and between each pair of main wheels.
4. An aeroplane having a mounting consisting of two pairs of wheels arranged in transversely spaced relation, a smaller wheel in rear of and between each pair of main wheels, and a similar wheel for each pair of main wheels disposed in front and between each pair of main wheels, two cabins disposed beneath the central wing and spaced from each other longitudinally of said central wing, and a cabin between said central wing and top wing positioned intermediate of said first cabins.
5. An aeroplane having three sets of wings arranged in vertically spaced relation, the middle wing being considerably longer than the remainder and the top wing being longer than the lower wing, and each wing being composed of horizontally spaced relatively narrow plates, two cabins disposed beneath the central wing and spaced from each other longitudinally of said central wing, and a cabin between said central wing and top wing positioned intermediate of said first cabins, and traction propellers at the front and rear of each of said pair of cabins, and a propeller in front of the cabin between the central and upper wings, said cabin be-

tween the central and upper wings forming the body of the aeroplane and extending rearwardly beyond said transversely spaced cabins, and a rudder on the end of said cabin, each of the said lower cabins having a mounting consisting of a pair of wheels, a smaller wheel in rear of and between said pair of main wheels, and a similar wheel disposed in front and between said pair of main wheels.

In testimony whereof I have hereunto signed my name to this specification.

CHARLES PETRUNIN.
